UNITED STATES PATENT OFFICE.

JOHN S. KIMBALL, OF SAN FRANCISCO, CALIFORNIA.

CONCRETE PILE-COVERING.

No. 927,357.

Specification of Letters Patent.

Patented July 6, 1909.

Application filed March 2, 1909. Serial No. 480,830.

To all whom it may concern:

Be it known that I, JOHN S. KIMBALL, citizen of the United States, residing in the city and county of San Francisco and State 5 of California, have invented new and useful Improvements in Concrete Pile-Covering, of which the following is a specification.

My invention relates to a protecting covering for piles and like structures, and means 10 for applying and securing the same.

It consists of a series of substantially radially projecting bonds fixed in the pile, and a casing fitting over the ends of said bonding devices, being held in position so as 15 to leave an annular space around the pile, into which concrete or other plastic material, which will subsequently harden, is placed; this material firmly embedding the bonding devices, and thus locking it in many places 20 directly to the pile; the outer casing may afterward be removed, and subsequently re-employed.

My invention consists in combinations of parts, and details of construction which will 25 be more fully explained by reference to the accompanying drawings, in which—

Figure 1 is a view of the pile prepared for coating. Fig. 2 shows the pile with the bonding device and the exterior casing. 30 Fig. 3 shows the completed coated pile.

Many devices have been employed for protecting piles from the ravages of the teredo, or other marine worms or insects, and among these, concrete or similar material has been 35 applied. The difficulty with such applications is that on account of its rigidity and brittleness, it has not been possible to secure it so that it will not break or flake off and leave the part exposed.

My invention is designed to accurately 40 apply an even coating of such material around the pile, and to firmly lock it thereto at a great many points so that it cannot be broken or flaked off by rough contact from 45 the outside.

As shown in the drawing, A represents 50 the section of a pile sufficient to extend from high water mark to the mud in which the pile is to be embedded. Into this section I drive nails, spikes, or other bonding devices 55 2 in any suitable or desired form so that they are fixed firmly in the body of the pile. The

outer ends of these bonding devices are substantially at an equal even distance from the center, and extend as far away from the 55 pile as will equal the desired thickness of the material.

4 is a casing which may be made of metal or other suitable material sufficiently large to inclose the outer ends of the bonding 60 devices 2. The casing 4 may have its edges disengageably interlocked, or otherwise secured by flanges and bolts so that it can be subsequently removed. This casing 4 is fitted around the outer ends of the bonding devices 2, and is by them retained at the desired distance from the surface of the pile, thus forming an open space between the pile and the casing. This space is then 65 filled with the protective material 3, such as 70 concrete or other plastic material, which can be packed into the space, and which will afterward set or harden. The casing will extend from a point below the mud into which the pile is driven to a point above 75 high water mark, and when the protective coating 3 has been applied, it will cover the pile over this whole space. After it is properly set, the outer casing 4 may be removed 80 from it, or it may be allowed to remain, and if of metal would be gradually destroyed by the action of the water, and from other causes, but in either case the protective coating remains, and is firmly anchored to the pile at so many different points that it is 85 practically indestructible by the contact of floating vessels or floating objects which might otherwise cause it to break and flake off. Such a coating will preserve the pile 90 indefinitely.

Having thus described my invention, what I claim and desire to secure by Letters Patent is—

1. A protective coating for piles, and locking devices secured to the piles having their 95 outer ends embedded in the coating.

2. A pile having radially projecting bonding devices driven into it, and a protective coating of plastic material which will afterward set or harden surrounding the pile and 100 embedding the bonding devices.

3. The combination with a pile or like structure, of radially projecting bonding devices having their inner ends driven into the

pile, the outer ends projecting to approximately an equal distance therefrom, an exterior casing fitting over the ends of said bonding devices, and plastic material which 5 will afterward set or harden, filled into the casing and embedding the bonding devices.

In testimony whereof I have hereunto set

my hand in presence of two subscribing witnesses.

JOHN S. KIMBALL.
